ANTIBALLOON DEVICE

Filed Oct. 6, 1922

INVENTOR:

JOSEPH AUGUSTE ROUGE

John J. Moore
ATTORNEY.

UNITED STATES PATENT OFFICE.

JOSEPH AUGUSTE ROUGE, OF ST. ETIENNE-LES-REMIREMONT, FRANCE.

ANTIBALLOON DEVICE.

Application filed October 6, 1922. Serial No. 592,864.

To all whom it may concern:

Be it known that I, JOSEPH AUGUSTE ROUGE, a citizen of the French Republic, and a resident of St. Etienne-les-Remiremont, Vosges, France, have invented certain new and useful Improvements in Antiballoon Devices, of which the following is a specification.

My present invention has for its object 10 to provide an improved swinging thread bulging preventing device which is applicable to ring spinning devices used for spinning or twisting textile or similar materials.

A further object of my invention is to 15 provide a device of the kind mentioned which permits of less heavy runners being used, enables to spin on spindles of smaller diameter than heretofore, to reduce the tension or drag on the thread and thus increase production.

In the accompanying drawings I have illustrated by way of example one form of construction of my invention. In these drawings:

25 Fig. 1 is a sectional elevation showing a spindle provided with my thread bulging preventing device supported on the ring carrying slide.

Fig. 2 is a similar view showing a construction having an additional special support for the thread bulging preventing device, this arrangement being applicable in devices in which the ring carrying slide is not sufficiently wide.

35 Fig. 3 is a top plan view of Fig. 2, the spindle rotating to the right hand.

Fig. 4 is a similar plan view showing the spindle rotating to the left hand.

Fig. 5 is a plan view of a modified form 40 of support.

In ring spinning or twisting devices the thread from the drawing rollers passes through a guide-ring K, then into a runner T and the end thereof is fastened to the 45 cop P which is to be built on the spindle B.

The spindle B and therefore the cop P having a very quick rotary movement, the thread causes the runner T to move on the ring M at a rate of speed nearly equal to 50 that of the spindle. This variable speed (about 11,000 revolutions per minute) produces its action of centrifugal force on the thread and runner, whereby the thread is caused to bulge as shown in A between the 55 guide-ring K and runner T.

This bulging is prejudicial and does not permit of the desired grade of textile thread being produced.

The device forming the subject matter of my present invention is particularly conceived to annul the prejudicial force of the bulging by making it eccentric with relation to the axis of the spindle.

The characteristic feature of my invention resides in the arrangement of a rigid wire F in the path of the bulging in order to annihilate the same, said wire F being of suitable diameter and shape and inclined with relation to the horizontal plane of the ring.

In the construction shown in Fig. 1, said rigid wire F is supported and guided on its ends S, extending into oval holes O in the ring carrying slide N. Therefore during its alternate raising and lowering movements, said wire will moreover be carried away by said slide.

On the other hand said wire is allowed to swing in the oval holes O and thus move away from the spindle under a very slight pressure, in order to allow the usual working of the device, then come back automatically by its own weight or gravity to the operative position.

In devices in which the ring carrying slide 85 is not of sufficient width, I use an additional support H screwed onto said slide. Such an arrangement is shown in elevation in Fig. 2 and in top plan view in Figs. 3 and 4. Said support or bracket H is formed of a 90 yoke shaped member, around the cross bar of which is wound the end of the wire F forming the thread bulging preventing device. In this arrangement the wire F is adapted to freely swing around the cross bar 95 of said yoke H. Two stops R₁ and R₂ are provided to limit the swinging movements of the device in either direction.

An alternative form of bracket H' is shown in Fig. 5, wherein said bracket has loops 100 V forming substitutes for the oval holes O in the ring carrying slide N (Fig. 1). In this construction the anti-bulging device is adapted to swing in said loops or eyes V.

In either form of construction described, 105 that is whether the anti-bulging device is adapted to freely swing in oval holes in the slide, or in loops or eyes or around a shaft or bar, said device will always be held or brought back to its operative position F₁ by 110

gravity. Under a slight pressure due to the bulging, said device will be brought to the unstable position F_2 , to clear the vertical stroke of the ring. Around said position F_2 , the anti-bulging device owing to its extreme movableness is subject to small swinging movements which act to regularize the tension of the bulging with great elasticity. In this way I obtain a textile thread which is more regular than thread spun without my improved device.

The rigid wire which forms my anti-bulging device may be cranked and have two or more points in contact with the bulging thread.

Having now fully described my said invention, what I claim and desire to secure by Letters Patent, is:

1. The combination with a ring spinning or twisting device, of an anti-bulging element mounted for swinging movement under the action of the ballooning thread, and normally held by gravity in position to prevent thread bulging during operation of the device.

2. The combination with a ring spinning or twisting device, of an anti-bulging element mounted for swinging movement under the action of the ballooning thread, and normally held by gravity in position to prevent thread bulging during operation of the de-

vice, and means to limit the swinging movement of said element.

3. The combination with a ring spinning or twisting device, of an anti-bulging element mounted for swinging movement on said device, comprising a wire length inclined with respect to the work to be produced by the device, said wire length being mounted for free swinging movement relative to the device.

4. The combination with a ring spinning or twisting device, including a ring carrying slide, of a bracket secured on said slide, a shaft on the bracket, and an anti-bulging wire element swingingly mounted on said shaft.

5. The combination with a ring spinning or twisting device, including a ring carrying slide, of a bracket secured on said slide, a shaft on the bracket, and an anti-bulging wire element swingingly mounted on said shaft, said element being formed with means to cooperate with the slide to limit the swinging movement of the element in one direction.

In testimony whereof I have hereunto set my hand in presence of two witnesses.

JOSEPH AUGUSTE ROUGE.
